UNITED STATES PATENT OFFICE.

ALFRED DOUGLAS WESTMAN, WILLIAM HENRY WESTMAN, JAMES NELSON RICHARDS,
AND ROSS HUFF, OF CHATHAM, ONTARIO, CANADA.

TRACK-HINGE FOR SWING-POLES.

1,179,485.

Specification of Letters Patent. Patented Apr. 18, 1916.

Application filed February 6, 1914. Serial No. 817,064.

To all whom it may concern:

Be it known that we, ALFRED D. WESTMAN, WILLIAM H. WESTMAN, JAMES N. RICHARDS, and Ross HUFF, citizens of Canada, residing at Chatham, in the county of Kent and Province of Ontario, Canada, have 5 jointly invented new and useful Improvements in Track-Hinges for Swing-Poles, of which the following is a specification.

10 Our invention relates to improvements in track hinge for swing pole; and the objects of our improvements are to facilitate the quick removal of litter from the stables without disconnecting the track, so far as 15 we know in swing poles at present in use the hanger carrying the litter carrier must be run out on the track before the pole can be swung around to deposit the litter where desired, after the litter carrier is emptied, the pole must be swung 20 back to its former position before the carrier can be returned into the stables.

We attain these objects in the manner as illustrated in the accompanying drawing, in 25 which;

Figure 1, is a top view of the hinge arm or projecting bracket and inner end of pole; Fig. 2, is a side view showing how the track is hung to the bracket and swing 30 pole; Fig. 3, is a side view of the upper braced hanger of which Fig. 4, is a front view; Fig. 5, is a view from below, showing the relative position of the track to the projecting bracket and pole when the pole 35 is straight out or swung either way as indicated by the arrows; Fig. 6, is a section through 1—2 of steel casing "J" shown in Figs. 2 and 5 showing the sliding track within said casing.

40 Similar letters refer to similar parts throughout the several views.

Referring to Figs. 1 and 2, "A" is a hinge arm bracket projecting from and bolted to the wall "N", over the doorway, 45 and secured by braces "I". The swing pole "B", of any desired length is attached at the inner end to the arm "A" by hinge plates "E", and center bolt "D", the outer end of pole being held up by guy rods "M—M" hung from a ring "L" of hanger "K" in Figs. 3 and 4. The end of hanger "K" is vertically above the bolt "D" to 50 keep the pole level when swinging. The track "F" is attached to the bracket "A"

and pole "B" by means of hangers C. C. on 55 which the hangers "H" of litter carrier run. In some swing poles the track must be disconnected at or near the wall line when required to swing the pole, in others there are intricate sections between the stationary 60 tracks which easily get out of order. To overcome these difficulties we have a flexible sliding track "G", preferably composed of two pieces of thin steel springs attached together at one end to the hanger "C" of 65 pole "B", the other end sliding into a steel casing connected to either end of stationary track and bolted to the hanger "C" of the bracket "A", thus forming a continuous track. When the pole is at a right angle to 70 the building and the track in a straight line, the loose end of flexible sliding track is partly in the steel casing as shown by slot "O" Fig. 2, leaving a space "P" Fig. 5; this allows the end of flexible sliding 75 track to recede and slide over the bolt fastening the casing to the hanger when the pole is swung either way. This enables the carrier to be moved around the corners and dumped where desired and returned into 80 barn without disconnecting the pole, whether it be straight out or parallel with the wall of building or any angle between these points.

As considerable variation is possible in the details of construction of our improved 85 device without departing from the spirit of our invention, we do not intend to limit ourselves to the specific form herein shown and described.

What we claim as new in connection with 90 a swing pole track and desire to secure by Letters Patent, is:—

1. The combination of a flexible sliding track with a steel casing as part of the 95 track.

2. The combination of a projecting bracket, with a flexible sliding track and a steel casing as part of the track.

3. The combination of a braced hanger with a projecting bracket, a flexible sliding 100 track and a steel casing as part of the track.

ALFRED DOUGLAS WESTMAN.

WILLIAM HENRY WESTMAN.

JAMES NELSON RICHARDS.

ROSS HUFF.
